IDENTIFICATION CARD HOLDER

George E. Steinmetz, Tiffin, Ohio

Application March 14, 1935, Serial No. 11,147

1 Claim. (Cl. 150—35)

This invention relates to card holders and more particularly identification card holders.

The primary object of this invention resides in the provision of a card holder adapted to retain an automobilist's license card on a key or other similar pocket case, ring or chain, so it can be readily displayed to identify the owner thereof when demanded by a police officer.

Another object of this invention resides in the provision of a license card holder adapted to be retained in a key or other similar pocket case so as to display identification information from both sides thereof upon being ejected from the case.

A further object of this invention resides in the provision of a license card holder adapted to be secured on one of the key retaining elements of a key or other similar pocket case so as to prevent accidental displacement of the license card therefrom while in its ejected position from the key case.

A still further object of this invention resides in the provision of a license card holder for key or other pocket cases adapted to be secured on the case so it can be completely concealed when in normal position and ejected therefrom to fully disclose the identification information thereof without subjecting the license card therein to the possibility of damage in handling the same.

In addition to the aforesaid objects this invention resides in the provision of a license card holder for key or other pocket cases adapted to be journaled therein so as to permit the card holder to be swung to the exterior of the case to display the information on the license card therein and to permit removal and replacement of the license card after inspection by an officer of the law.

Included among the objects of this invention is the provision of a license card holder adapted to be permanently secured to a key or pocket case in such position the information on the license card will be displayed upon opening the case.

With these and other objects in view this invention resides in the provision of a license card holder for key or other pocket cases which consists of certain novel features of construction to be hereinafter set forth in the specification, illustrated in the accompanying drawing and pointed out in the appended claim and, while this disclosure depicts my present conception of the invention, the right is reserved to resort to such changes in size and construction as come within the scope of the claim.

In the accompanying drawing forming a part of this application:

Fig. 1 is a perspective view of one type of key case showing the card holder forming the subject matter of this invention secured in normal position therein, certain folds of the key case being shown in opened position.

Fig. 2 is an enlarged vertical sectional view of the license card holder per se, the same being taken approximately on line 2—2 of Fig. 1.

Fig. 3 is an enlarged horizontal sectional view of the license card holder per se, the same being taken approximately on line 3—3 of Fig. 1.

Fig. 4 is an enlarged sectional view of the opened end of a modified form of license card holder showing a license card in dotted lines as being inserted in the holder.

Fig. 5 is a further modified form of the license card holder, the same being secured within the key case and showing the license card as being inserted therein.

In the present embodiment of this invention, the letter C and C' designate two different types of well known key cases, the former of which is provided with a key pin or the like P and a snap fastener S, while the latter, among other elements, is provided with key hooks or the like H. Although this invention is illustrated in conjunction with the above types of key cases, the same is applicable to other types of key cases or the like wherein the salient features and advantages thereof may be attained.

Journalized on the aforesaid key pin P of the key case C is a license card holder designated, in general, by the numeral 5 and is preferably constructed from a piece of material 6 having cut-out portions 7 which are disposed in opposed relation to one another and closed by transparent panes of celluloid or other suitable material 8 sewed or otherwise secured to the material by 40 stitches 9 or other suitable fastening means.

The aforesaid card holder is provided with elongated tongues 10 extending beyond the stitching 9 at one end thereof and have opposed eyelets 11 adjacent their extremities to accommodate the key pin P of the key case C so the card holder can be rotated on the key pin for ejection from the key case to inspect the license card disposed therein between the opposed panes 8. Through the instrumentality of the aforesaid structure the license card within the card holder will be protected both in normal and ejected positions yet fully displaying both sides of the license card when swung to its ejected position.

This card holder is adapted to accommodate 55

the license cards of the various States as by properly folding them or otherwise arranging them to permit the functions of this invention to be practiced.

- 5 Referring to Fig. 4 is a modified form of card holder which has a single tongue 10' at one end thereof in which is secured an eyelet 11' to accommodate the key pin P of the key case and, through the elimination of one of the tongues 10
- 10 illustrated in Figs. 1, 2 and 3, a license card R, indicated by dotted lines, can be removed and replaced without dismounting the card holder from the key pin or other securing element thereof.
- 15 As disclosed by Fig. 5 a card holder 5' is shown permanently secured to a key case C' having key hooks H and, through the instrumentality of this construction, a license card indicated by the letter R may be inserted in the card holder from an open side thereof.
- 20 With this invention fully set forth it is manifest that a license card holder is produced which

will assure automobilists of having in their possession identification information while driving their automobiles and, through the particular arrangement and construction of the card holder, it can be readily displayed without damage by handling 5 the same.

Having thus fully described this invention what I claim and desire to protect by Letters Patent is:

The combination with a key case consisting of opposed folding flaps, a pocketed window license 10 card holder having one edge open, opposed apertured ears formed on the open end of the license card holder; a key supporting pin passing through the opposed flaps of the key case at one edge thereof and the apertures in the ears of the license card holder to simultaneously pivot the license card holder for edgewise rotation between the flaps and close the open end of the pocket of the license card holder, and a closing flap formed on one of the opposed flaps of the key case. 15 20

GEORGE R. STEINMETZ.
